UNITED STATES PATENT OFFICE.

HERBERT J. CRABBS, OF PITTSBURGH, PENNSYLVANIA, ASSIGNOR TO WESTINGHOUSE ELECTRIC & MANUFACTURING COMPANY, A CORPORATION OF PENNSYLVANIA.

FUSE BLOCK.

Application filed June 10, 1922. Serial No. 567,319.

To all whom it may concern:

Be it known that I, HERBERT JOHN CRABBS, a citizen of the United States, and a resident of Pittsburgh, in the county of 5 Allegheny and State of Pennsylvania, have invented a new and useful Improvement in Fuse Blocks, of which the following is a specification.

My invention relates to fuse blocks and 10 particularly to blocks for supporting expulsion fuses such as are used in high potential circuits and mounted outdoors on poles.

One object of my invention is to provide 15 a simple block for supporting expulsion fuses that may be attached to insulators of the pin type.

A further object of my invention is to provide a fuse block of simple and relatively inexpensive construction that may 20 be readily secured to pin type insulators with a minimum of manipulation.

A further object of my invention is to provide a relatively elastic clamping device 25 whereby the fuse block may be tightly secured to the insulator in such manner that it will not become loosened by constant whipping of the conductors attached to the block.

These and other objects, that will be made 30 apparent throughout the further description of my invention, are attained by means of the fuse blocks hereinafter described and illustrated in the accompanying drawings, wherein:

5 Figure 1 is an elevational view of an expulsion fuse structure mounted upon the improved form of fuse block;

Fig. 2 is an elevational view of a bracket 0 constituting a part of the block, and

Fig. 3 and 4 are plan and side views, respectively, of the bracket shown in Fig. 2.

Referring to the drawings, the apparatus 5 includes a pair of pin type insulators which are of substantially standard construction and are mounted upon pins or bolts 6 that are secured to cross arms 7 that may be mounted upon a pole or support in the usual manner. The insulator is provided with a circumferential groove 8 disposed between an annular bead 9 and an apron 10. A transverse groove 11 extends across the top of the insulator and communicates with the groove 8.

The fuse block comprises a bracket 12 having a flat disc-like base portion 13 that

is adapted to rest upon the flat surface 14 on the end of the insulator. The bracket is preferably made of malleable iron or metal having ductile characteristics and is provided with a web 15 that terminates in tongues 15^a which extend into the groove 11 and across the circumferential groove 8, as indicated in Fig. 1.

A flexible clamp ring 16, having its ends provided with integral eyelets 17, is disposed in the annular groove and embraces the ends of the tongues 15^a. The ring is normally of greater diameter than the bead 9 so that it may be slipped thereover when the ring is being assembled upon the bracket. 70

The ends of the ring 16 are drawn toward one another by means of a threaded bolt 18 and a threaded nut 19 mounted thereon. Tightening of the bolt draws the annular ring 16 into engagement with the inclined under surface of the bead 9 and, consequently, tends to draw the bracket securely into engagement with the flat face 14 of the insulator. 75

The web 15 and the tongues 15^a lying within the groove 11 prevent any tendency of the bracket to rotate about the axis of the groove 8. Therefore, when the brackets are secured to their respective insulators, their relative position will be permanently 85 maintained.

As indicated in the drawings, the bracket is provided with a perforation 21 through which a bolt 22 extends for securing a fuse clamp 23 thereto. The clamp 23 comprises 90 a flat metal plate having a pair of U-bolts 24 which surround the fuse cartridge 25 and constitute a clamp for supporting it in any desired position. The fuse cartridge may be of any standard construction. 95

The bracket 12 is further provided with an opening 26 through which the end of a conductor 27 is looped, as indicated in Fig. 1, the purpose being to provide an anchor for the conductor at a point substantially coincident with the axis of the insulator so that the conductor can exert no strains tending to relatively displace the insulator or the bracket. As indicated, the conductor is tied to the bracket and the free end is 100 then connected to the terminal 28 of the fuse cartridge. 105

It will be apparent that the fuse cartridges constituting an expulsion fuse may be adjusted at any angle with respect to one 110

- another and that the cartridges may be adjusted longitudinally of the clamp 23 so that the distance between the ends of the fuses may be varied. As indicated, the 5 fuses are disposed at a slight angle with respect to one another and, when a fuse is burned, the resultant streams of gases discharged from the cartridges pass one another and tend to blow away the arc.
- 10 I have shown the bracket as employed for supporting expulsion fuse cartridges, but it is apparent that the bracket may be designed for supporting various electrical devices, such as switches, bus bars and other types 15 of fuses.

While I have described and illustrated but one embodiment of my invention, it will be apparent to those skilled in the art that various changes, modifications, substitutions, 20 additions and omissions may be made therein without departing from the spirit and scope of my invention, as set forth in the appended claims.

I claim as my invention:

- 25 1. In a fuse block, the combination with an insulating support having a circumferential groove and a transverse groove in the end of the support and communicating with the first groove on opposite sides of the support, of a bracket for the fuse engaging the end of the support and having oppositely disposed tongues extending into the opposite ends of the transverse groove and across the circumferential groove and an adjustable 30 annular clamp member fitting within the circumferential groove and over the said tongues for clamping the bracket to the support.
- 35 2. In a supporting block for an electrical device, the combination with an insulating support having a circumferential groove and a transverse groove in the end of the support and communicating with the first groove on substantially opposite sides of the support, of a bracket for the said device 40 engaging the end of the support and hav-

ing oppositely disposed tongues extending into the opposite ends of the transverse groove and across the circumferential groove and an adjustable annular clamp member fitting within the circumferential groove and over the said tongues for clamping the bracket to the support.

3. In a fuse block, the combination with an insulating support having a circumferential groove and radial grooves in the end 55 of the support communicating with the first groove, of a bracket for the fuse engaging the end of the support and having tongues extending into the radial groove across the circumferential groove and an adjustable annular clamp member fitting within the groove and over the said tongues for clamping the bracket to the support.

4. In a supporting block for an electrical 60 device, the combination with an insulating support having a circumferential bead at one end having notches therein, of a bracket for the device engaging the end of the support and provided with tongues extending 65 into the said notches and beyond the bead and an adjustable annular clamp member normally of greater diameter than that of the bead and adjustable to a smaller diameter than that of the bead for engaging 70 the tongues and clamping the bracket to the support.

5. In a supporting block for an electrical 75 device, the combination with an insulating support having a circumferential bead at one end having notches therein, of a bracket for the device engaging the end of the support and provided with tongues extending 80 into the said notches and beyond the bead and an adjustable annular clamp member engaging the bead and extending over the 85 said tongues for clamping the bracket to the support.

In testimony whereof, I have hereunto subscribed my name this first day of June, 1922.

HERBERT J. CRABBS.
